UNITED STATES PATENT OFFICE.

DIONISIO ARTAMENDI, OF BARCELONA, SPAIN, ASSIGNOR TO BERISTAIN & CIA, OF BARCELONA, SPAIN.

AUTOMATIC PISTOL.

1,416,671.

Specification of Letters Patent. Patented May 23, 1922.

Application filed March 30, 1921. Serial No. 457,018.

To all whom it may concern:

Be it known that I, DIONISIO ARTAMENDI, a subject of the King of Spain, residing at Barcelona, Spain, have invented certain new and useful Improvements in Automatic Pistols, (for which I have filed applications for patents in Spain on March 25, 1916, August 1, 1918, and July 10, 1919; in Belgium on April 17, 1917, and June 7, 1919; in Germany on April 13, 1917, and in Italy on June 26, 1919;) and I do hereby declare the following to be a full, clear, and exact description of the invention, such as will enable others skilled in the art to which it appertains to make and use the same.

My invention relates to automatic pistols and more especially to the type of automatic pistols provided with a hammer which at the moment of firing strikes the cartridge either directly or by means of a firing pin.

An object of my invention is to provide an improved automatic pistol having greater safety properties than those heretofore known and in which the firing can only occur when the operator grasps the firearm to fire, thus avoiding any possibility of involuntary firing.

Another object of this invention is to furnish an automatic pistol which stays automatically in safety at the moment in which the cartridge magazine is drawn aside, thus avoiding the possibility of firing of the cartridge occupying the barrel, when the cartridge magazine is drawn aside.

My invention consists essentially in providing the rear part of the head of the hammer with a tooth or hook and in combining the rear part of the grip of the pistol with a grip or pressure lever pivotally mounted at the lower part of the grip, and being at its upper part provided with a hook which can catch and hold the tooth of the head of the hammer. This grip lever is moved in one direction by a spring which keeps it normally in the position which holds the hammer, thus preventing the accidental firing of the firearm. The grip lever extends rearwardly of the rear part of the grip of the firearm, to such a position, that when the operator grasps the firearm for firing, he exerts pressure upon the grip lever and releases the hammer.

Besides, the invention consists in arranging at one side of the grip of the arm, an os-

cillating lever adapted to engage the cartridge magazine in such a manner that when the magazine is in its place, this oscillating lever allows the free operation of the firearm, but when the magazine is drawn aside, the lever oscillates and prevents the operation of the trigger and of the grip lever.

The invention will be explained by the following detailed description with reference to the accompanying drawing in which:

Figure 1 is a longitudinal sectional view of an automatic pistol embodying my invention.

Figure 2 is a similar view of another embodiment of the invention.

In Fig. 1 my invention is shown as incorporated in a pistol of the well known type, in which the reaction spring is disposed around the barrel. In this figure, 1 represents the breech slide and 2 the barrel, upon which is coiled the reaction spring 7, which at its rear end bears on the shoulder 8 of the barrel and at its front end bears upon the collar 3 concentric to the barrel. This collar 3 is fixed to the end of the breech-slide 1, in the well known manner, by a bayonet locking joint including the teeth 5, which cooperate with the circular groove 6 of the breech-slide, its position being determined by the flange 4 of the sleeve and the corresponding shoulder of the breech-slide.

Figure 2 shows an embodiment of the invention in a pistol of the well known type in which the reaction spring is disposed beneath the barrel. In this figure, 31 is the breech-slide, 32 the barrel and 37 is the reaction spring, which is disposed around the bolt 38 and bears at its forward end upon the breech-slide 31 and at its rear end upon the head of the bolt 38.

Both the form of construction of the Figure 1 and that of the Figure 2 are provided, in a well known manner, with the usual safety device 20 which renders the trigger 19 inactive.

My invention consists in providing these pistols with an automatic safety device constituted by a pressure or grip lever 21, disposed in the rear part of the grip of the firearm. This lever has its lower end pivotally mounted on a pin 22, and carries at its upper part a tooth 26, bearing on the frame 27 of the pistol to limit the rearward movement of the grip lever and to determine its normal

position. The grip lever 21, is actuated by the same spring which actuates, in a well known manner, the impeller 23 of the hammer 24. This spring is not shown in the drawing in order to simplify the latter. This spring operates upon the downwardly extending portion of the lever 21 near the pin 22.

The grip lever 21 is formed with a hook 28 which catches directly in the hook 25 of the rear part of the head of the hammer, so that when the mechanism is in the position shown in the drawing, the hook 28 locks the hammer preventing its function even when the trigger 19 be actuated.

The grip lever 21 also carries a forwardly extending abutment 17 adapted to cooperate with the oscillating lever 10. This lever 10 can oscillate around a pin 11 and is moved in one direction by a helical spring 18, which engages its lower end.

The upper end 14 of the lever 10 is arranged in close proximity to the rear end of the connector 15, and the lever 10 has an arm 12 arranged near its upper end, which due to the action of the spring 18, bears upon the cartridge-magazine 13. The frame of the pistol has a recess 16 in which the abutment 17 travels, the end of this abutment terminating close to the lever 10.

The spring 18 pushes the lower end of the lever 10 and causes the arm 12 to engage the cartridge-magazine 13. When the cartridge-magazine is placed in the pistol, as shown in the drawing, the arm 12 of the lever 10 is engaged by the cartridge-magazine 13 and this causes the upper end of the lever 10 to move out of the path of movement of the connector 15 and of the abutment 17 of the lever 21, so that on grasping the pistol the grip lever 21 can be moved forwardly so as to unhook the hammer 24 thus permitting firing when the trigger 19 is pressed by the finger of the operator.

On the contrary, if the cartridge-magazine 13 is drawn aside, the arm 12 of the lever 10 loses its support, and the lever 10 oscillates owing to the action of the spring 18, and then the body of the lever 10 is brought to a position in front of the abutment 17 of the lever 21, so that even when the pistol is grasped, it is impossible to oscillate the grip lever 21 to unhook the hammer 24 and, therefore, the firearm cannot be fired. At the same time, the end 14 of the lever 10 is brought into a position in the path of movement of the connector 15, thus preventing the movement of the connector and therefore of the trigger 19.

Thus when the cartridge-magazine 13 is drawn aside, any firing of the pistol is absolutely prevented because the trigger can not be actuated and on the other hand, even in the case of it being possible to actuate the trigger 19, the grip lever 21 is locked, and

therefore the hammer 24 would remain withheld by the hook 28 and prevent firing.

From the description of this invention, it will be understood that with this device, absolute safety of automatic pistols is obtained, and the mechanism prevents at all times an involuntary firing of the pistol, because the firearm stays automatically in safety when the cartridge-magazine is drawn aside or when the operator ceases to exert pressure on the grip.

Although I have described a preferable and convenient form of my invention, it will be understood that slight changes can be introduced without varying the character and the scope of the invention as expressed in the claims.

I claim:

1. In an automatic pistol of the class described, a grip lever pivoted in the rear portion of the grip of the pistol and actuated by the same spring that actuates the hammer, in such manner that it projects normally from the grip, a hook at the rear part of the head of the hammer, another hook at the upper end of said grip lever adapted to normally engage the hook of the hammer and thus prevent firing while the grip lever is not grasped by the operator, a pivoted oscillating lever provided with an arm which bears upon the cartridge-magazine and is actuated by a spring which causes it to oscillate when the cartridge-magazine is drawn aside, a trigger connector, the oscillating lever having its head arranged in close proximity to the end of the connector in such manner that on drawing away the cartridge-magazine, the last mentioned lever oscillates and its head is interposed in the path of the connector, thus preventing the firing of the pistol.

2. In an automatic pistol of the class described, a grip lever having its lower end pivotally mounted in the rear part of the grip of the pistol, said lever normally projecting from the grip, a hook at the upper end of said grip lever, another hook at the rear part of the head of the hammer and adapted to be engaged by the hook of the grip lever, an oscillating lever normally bearing upon the cartridge-magazine, a spring for moving said oscillating lever in one direction when the cartridge-magazine is withdrawn, a trigger connector, the end of said oscillating lever being interposed in the path of the connector when the lever oscillates due to the withdrawal of the magazine, and an abutment on the grip lever disposed in such manner that when the oscillating lever oscillates due to the withdrawal of the cartridge-magazine said abutment strikes against the oscillating lever and prevents operation of the grip lever.
